UNITED STATES PATENT OFFICE

150,484

DESIGN FOR A TOY STATIONARY ENGINE

Raymond R. Zimmer, Chicago, and Harold L. Snavely, Oak Lawn, Ill.; said Zimmer assignor to said Snavely

Application December 14, 1946, Serial No. 135,508

Term of patent 3½ years

(Cl. D34—15)

To all whom it may concern:

Be it known that we, Raymond R. Zimmer and Harold L. Snavely, citizens of the United States, residing respectively at 4249 North Wolcott Avenue, in the city of Chicago and 9613 South 52nd Avenue, in the village of Oak Lawn, county of Cook, and State of Illinois, have invented a new, original, and ornamental Design for a Toy Stationary Engine, of which the following is a specification, reference being had to the accompanying drawing, forming a part thereof.

Fig. 1 is a perspective view of the toy stationary engine showing our new design.

Fig. 2 is an elevation of one side of the toy stationary engine.

Fig. 3 is an elevation of another side of the toy stationary engine.

We claim:

The ornamental design for a toy stationary engine, as shown.

RAYMOND R. ZIMMER.
HAROLD L. SNAVELY.
